FIG. 1.

FIG. 2.

FIG. 3.

UNITED STATES PATENT OFFICE.

HELMUTH V. ZENGEN, OF NEW YORK, N. Y.

BUILT-UP MONUMENT.

Application filed October 6, 1920. Serial No. 415,059.

To all whom it may concern:

Be it known that I, HELMUTH V. ZENGEN, a citizen of the United States, residing at New York, in the county of New York and 5 State of New York, have invented certain new and useful Improvements in Built-Up Monuments, of which the following is a specification.

My invention relates to statuary or 10 monumental work, and more particularly stated contemplates a novel built-up structure for garden, cemetery and other decorative purposes.

An object of the invention is to produce 15 a monument, the development of which is obtained by erecting a suitable frame structure upon any convenient foundation, and applying to said frame structure certain courses or strata of materials which are 20 gradually formed through the skill of a workman into various aesthetic figures and artistic groupings.

Another object of the invention resides in 25 the method of building up an article or figure from plastic material such as concrete for example, at the place of erection, thereby eliminating the heretofore tedious casting processes and expensive studio work which latter have in the past been the cause 30 of limiting a more general use of decorative statuary.

My invention further consists in the comparatively simple and inexpensive means 35 employed to quickly construct a monument or similar structure as will more fully hereinafter appear and be pointed out in the appended claims.

In the accompanying drawings which I 40 have used to illustrate one of many embodiments of my invention and in which similar reference characters designate corresponding parts in the several views:

Fig. 1 is a view showing a completed 45 work constructed in accordance with my invention;

Fig. 2 is a view illustrating a form of 50 skeleton frame work which can be used in building up the figure shown in Fig. 1; and

Fig. 3 is a horizontal sectional view on the 55 line 3—3 of Fig. 1 on a slightly larger scale, showing the several strata or applications of materials utilized in building up the monument.

In the building up of a monument or 60 other decorative art work, such for example

as that required to beautify a garden, I first lay out a suitable foundation upon the site selected and upon this foundation proceed to erect the work. A stone base or pedestal 60 1 may be provided as shown in the drawings, it being understood, however, that this can be varied or entirely eliminated according to the requirements and nature of the work.

A slab 2 is preferably mounted upon the 65 base 1, and a main frame 3 extends upwardly from the said slab.

The main frame 3 is formed of relatively heavy rods or piping 4, and at the base is formed with off-set portions 5 designed to 70 give greater stability to the structure. The rods 4 are bent to conform to the figure or work selected, and as shown herein extend upwardly, being bent to form a relatively rigid interior supporting frame, the terminating ends of said rods being indicated by 75 the numeral 6. The rods may be joined together at intervals as shown at 7.

A relatively lighter or supplementary frame 8 is secured to the main frame 3, and 80 this frame is designed to conform to the general contour of the prominent features of the work being constructed. The supplemental frame 8 is joined at numerous places to the main frame as indicated by the 85 numeral 9. This may be accomplished by wrapping the material forming the frame 8 about the rods 4 or otherwise securing them together as will be understood.

Upon the frame sections 3 and 8 I now 90 construct an interior body portion 10, the contour of which can be shaped to approximate the outline of the figure. This portion of the work may be termed a dummy and the materials of which it is formed may be 95 any well known filling substances, such as hay, straw, saw-dust, rags, or other conveniently obtained material.

A wrapping 11 is provided to keep the filling material in position upon the frame 100 sections, this wrapping being in the form of wire which may be joined to the frame sections at suitable intervals as indicated at 12.

The body portion is packed and wrapped in a compact manner and over this material 105 I apply a covering 10' formed of fabric saturated with a mixture of plastic material such as cement. The fabric may be sack rags for example, or other fibrous material capable of absorbing a relatively large de- 110

gree of the plastic material. In practice these rags are dipped in a solution of cement and water after which they are applied by wrapping or binding, and then allowed to harden about the body portion of the figure.

Upon this covering I now apply a course of cement 13 working the same by hand into the several configurations of the body portion to any desired thickness. In practice I have found that varying thicknesses for the coating of cement to the extent of from four to six inches provides a thoroughly stable coating and at the same time permits of great latitude in shaping the figure.

The ingredients forming the coating may be for example, two parts fine ashes, one part gravel, and one part Portland cement, or for varying thicknesses proportions of 20 two and one half parts sand and one part cement.

An outer surface finish 14 is applied to the cement course 13 preferably composed of pumice and cement spread in relatively 25 thin coats of varying fractions of an inch.

Cement suitably colored may also be used, giving various tints of gray, white, cream, and other effects to the finished work. The proportions and character of the plastic or 30 hydraulic setting materials may be varied as will be understood, and I do not limit myself to the exact disclosures herein set forth.

From the foregoing it will be obvious that 35 I have produced an easily constructed cementitious monument, capable of being configured by the hand as distinguished from casting, and further that such configurations can be attained at the place of 40 erecting the monument thereby reducing the time and expense in obtaining decorative works of art to a minimum.

I claim:

1. A decorative built-up and configured 45 monument comprising a supporting frame formed of wire bent to conform to the outline of the configurations of the monument, a body portion formed of a filling material wrapped with saturated cementitious material 50 and a coating for the aforesaid materials, said coating forming the completed configurations of the monument.

2. A decorative built-up monumental figure comprising a supporting frame bent to 55 conform to the outline of the figure produced, a body portion of fibrous filling material, a wrapping for said filling material composed of fabric saturated with a hydraulic setting compound and another coating 60 of hydraulic setting material covering the aforesaid materials, said last mentioned

coating forming the decorative features of the figure.

3. A cementitious built-up figure comprising an interior body portion including a 65 supporting frame, filling material, and a course of cementitious material adapted to be shaped to conform to the general outlines of the figure to be produced, and a coating of hydraulic setting material applied to the 70 said body portion, said hydraulic setting material being shaped to form the completed figure.

4. A cementitious built-up figure comprising an interior body portion including 75 a supporting frame, and filling material arranged about said frame and shaped to conform to the general outlines of the figure to be produced, a covering of relatively thick concrete applied to said body portion and 80 shaped to form the outlines of the completed figure, and a further covering of relatively thin cement for said concrete.

5. A cementitious built-up and configured monument including a base having a supporting frame secured thereto, a body portion of filling material secured to said frame and shaped to conform to the general outline of the configurations of the monument, a binding material covering said filling material, a relatively thick covering of hydraulic setting material for said binding material, said hydraulic setting material being shaped to the desired configurations, and a finishing coating for said hydraulic 95 setting material.

6. The herein described method of building up a decorative monument which consists in shaping a relatively soft interior body portion to generally conform to the 100 completed monument, wrapping said body portion with flexible material saturated with a hydraulic setting material, and shaping a coating of hydraulic setting material about said wrapping.

7. The herein described method of building up a decorative monument which consists in shaping a supporting frame to conform to the general outline of the completed monument; binding a body portion of soft material to said frame, then wrapping the aforesaid body portion with fabric saturated with a hydraulic setting material; then shaping a relatively thick coating of hydraulic setting material about said wrapping, and finally covering said last mentioned material with a relatively thin finishing coat of hydraulic setting material.

In testimony whereof I affix my signature.

HELMUTH V. ZENGEN.
